BRACELET

Henry Ferragamo, Cranston, R. I., assignor to
Edmund Recchia, Cranston, R. I.

Application July 19, 1947, Serial No. 762,061

1 Claim. (Cl. 63—4)

1

My present invention relates to the jewelry art, and more particularly to a novel construction of a bracelet.

The principal object of the present invention is to provide a bracelet having a novel link construction.

Another object of the present invention is to provide a bracelet having inter-connected stone settings with maximum flexibility.

A further object of the present invention is to provide a link bracelet that is simple in construction and easy and economical to manufacture and assemble.

With the above and other objects and advantageous features in view, my invention consists of a novel arrangement of parts, more fully disclosed in the detailed description following, in conjunction with the accompanying drawings, and more particularly defined in the appended claims.

In the drawings:

Fig. 1 is a front view of a bracelet embodying my invention;

Fig. 2 is a rear view thereof;

Fig. 3 is an enlarged section on line 3—3 of Fig. 1;

Fig. 4 is a perspective view of one of the settings;

Fig. 5 is a perspective view of one of the links; and

Fig. 6 is a plan view showing the link and setting assembly.

Bracelets for evening wear usually comprise a plurality of settings having real or imitation stones and closely connected by short links. This arrangement provides some flexibility, but the links are easily broken if the bracelet is flexed too greatly. Furthermore, because of the nature of the bracelet, manufacture and assembly are awkward. Usually, each setting is provided with oppositely disposed side openings and a plurality of settings are strung on a wire. The wire is flattened within each setting and then cut. The entire operation must be carefully performed and is wearing on tools and provides a lot of waste.

The present invention is designed to overcome these difficulties and provide a simple and easy method of manufacture and assembly and a bracelet having a great degree of safe flexibility.

Referring more in detail to the drawings illustrating my invention, my bracelet comprises a plurality of settings 10 connected by links 11, each setting having an ornamental stone 12 therein. It should be noted that the settings 10 may be of any desired shape to accommodate different stones 12. In the illustrated form, the diamond cut stone 12 requires a round setting 10.

Each setting 10 comprises a bottom 13, Fig. 4, integral sides 14, and tines 15 extending integrally from the sides 14 to retain the stones 12 in place. The bottom 13 of each setting 10 is provided with a transverse slot 16 having a central annular portion 17 wider than the slot 16.

Each link 11, Fig. 5, comprises a central bar

2

portion 18 bent upwardly at each end, and laterally extending heads 19 extending integrally from the bent ends of the portion 18. The heads 19 are shaped to fit the inner surface of the sides 14 of the settings 10 and in the illustrated form are arcuate in shape.

The above described settings and links may readily be formed from sheet stock. In assembly, a head 19 of a link 11 is pushed upwardly through the slot 16 of a setting 10. The link 11 is then easily twisted within the portion 17 of the slot and then turned until it assumes the position shown in Figs. 3 and 6. The head 19 is now snug against one side of the wall 14 and the bend in the bar portion 18 causes an offset, see Fig. 3, which permits the link to lie flat. A second link 11 is positioned similarly in the setting 10 opposite the first link 11 and settings and links are thus assembled until a complete bracelet is formed. The final links may be provided with a loop 20 and catch 21 for locking the bracelet to the wrist.

With the parts positioned as shown in Fig. 6, a stone 12 is placed in each setting 10 and the tines 15 bent inwardly to lock the stones in the settings, Fig. 1. As shown in Fig. 3, sufficient space exists between the stone 12 and heads 19 to permit movement of the heads upwardly to flex or bend the bracelet. However, the space is insufficient to permit twisting and withdrawal of the head. The stone thus provides a locking action.

While I have described a specific embodiment of my invention, it is obvious that changes may readily be made in the size, shape, or relative arrangement of parts without departing from the spirit and scope of my invention as defined in the appended claim.

I claim:

40 A bracelet comprising a plurality of settings, each of said settings having a radially extending slot in the bottom thereof, a plurality of links extending between said settings, each link comprising a narrow central portion having the end 45 portions thereof vertically offset and laterally projecting integral head portions extending from each end of the offset portions, said head portions being wider than said slots and the offset portions extending through said slots into said 50 settings, and an ornamental stone mounted in each setting, said stone extending into the setting and engaging the head portions to lock said links to said settings.

HENRY FERRAGAMO.
